UNITED STATES PATENT OFFICE.

LOUIS SWENINGSON, OF CLEVELAND, OHIO.

WRINGER.

Application filed April 24, 1925. Serial No. 25,482.

This invention relates particularly to a wringer for use in connection with power operated washing machines.

The primary object of the present invention is to provide a power operated wringer which shall be simple in construction, inexpensive to manufacture, and which shall be efficient and safe in operation.

Another object is to provide a wringer which shall include a pair of spring urged rolls, one of which is movable with respect to the other through the medium of a hand lever so that normally the rolls will be separated and inoperative to permit the washed articles to be easily inserted therebetween whereupon the hand lever may be depressed to engage the rolls to cause them to operate under spring tension in the usual manner. This arrangement in addition to facilitating the entrance of the washed articles between the rolls also provides a safety type of wringer as during such time that the articles are being entered, the rolls are inoperative and hence there is no danger of the fingers being caught therebetween. Furthermore if during operation the hand is accidentally caught between the rolls, the natural instinct is to release the hand lever whereupon the rolls will immediately separate and permit the hand to be withdrawn.

With these and other objects in view, the invention consists in the various novel features of construction and arrangement or combination, all of which will be fully described hereinafter and pointed out in the appended claims.

In the drawings accompanying and forming a part of this application, Fig. 1 is a top plan view of a washing machine equipped with a wringer constructed in accordance with my invention; Fig. 2 is a rear elevation of the wringer; Figs. 3 and 4 are vertical sectional views taken respectively on the lines 3—3 and 4—4 of Fig. 2; Fig. 5 is a side elevation of the wringer gear case; and Fig. 6 is a vertical sectional view taken on the line 6—6 of Fig. 5. Fig. 7 is a vertical sectional view similar to Fig. 3 but on a larger scale showing the parts as they will appear with a comparatively thin garment inserted between the rolls; and Fig. 8 is a view similar to Fig. 7, with the parts shown in an extreme position with a very thick garment inserted between the rolls.

Describing the various parts by reference

characters, 1 denotes generally a washing machine having a hinged cover 2 upon which is mounted an electric drive unit 3. This drive unit is provided with a clutch member 4 which is adapted to align with the wringer drive shaft 5 when the cover of the machine is raised.

The wringer consists essentially of two end brackets 7 arranged in spaced relation and each provided with an inverted U-shaped recess 8 and a clamp screw 9 threaded through one of the legs defining said recess. Each bracket is also provided with an antifriction bearing 10 which rotatably supports the lower wringer roll 11, a guide lug 12 for a purpose to be referred to hereinafter, and an elongated opening 13 which receives the ends of a hand lever operating shaft 14.

A pair of sub-brackets 16 also arranged in spaced relation are rotatably connected to shaft 14 adjacent the ends thereof. These brackets each carry an antifriction bearing 17 which rotatably supports the upper wringer roll 18, and each sub-bracket is also formed with an arcuate projection 19 which is preferably arranged slightly eccentric with respect to the longitudinal axis of shaft 14 about which the assembly is adapted to rock. The arcuate projections 19 are each adapted to engage beneath its respective lug 12 on the main brackets 7 and due to the aforementioned eccentricity of projections 19, the upper roll assembly may be rocked about the longitudinal axis of shaft 14 to cause the wringer rolls to engage. The top portion of each sub-bracket is also provided with a recess which is adapted to receive the end of a flat spring assembly 22. A metal strap 23, having an adjusting screw 24 threaded therein is arranged about the central portion of springs 22 and is connected to shaft 14 by a strap metal collar 25 pinned to the shaft and having the free end thereof engaged in an aperture in the depending end of strap 23. The washed articles are placed between the rolls and the lever 30 is depressed which rocks the upper roll unit about shaft 14 as an axis. When the lever 30 is depressed the shaft 14 is rotated and the collar 25, which is keyed to the shaft 14 (see Fig. 4) pulls downwardly on strap 23 which in turn tends to rotate the brackets 16 about shaft 14 due to the engagement of the springs 22 with the brack-

ets 16. The roll 18 is moved to the position shown in Fig. 7 and the shaft 14 rides upwardly in the elongated slots 13 a short distance depending upon the thickness of the 5 garment between the rolls. The lugs 12 engage the projections 19 on the roll 18 and tend to hold the roll in the position shown in Fig. 7 and at the same time permit the rolls to be separated against the tension of 10 springs 22 should a thick garment be passed between the rolls. This arrangement provides a resilient mounting for the upper wringer roll which may be varied by adjusting screw 24 to increase or decrease the 15 tension of springs 22. The springs 22 are maintained under slight tension when the wringer rolls are separated by pins 27 in shaft 14 engaging suitable shoulders 28 formed on sub-brackets 16 as shown in Fig. 20 1. The projections 19 being arranged eccentric to the longitudinal axis of the roll 14 it will be clear that the lugs 12 engage the projections 19 as shown in Fig. 7 and temporarily hold the rolls in the position 25 shown in this figure and when a thick garment is inserted between the rolls the shaft 14 being loosely mounted allows the rolls to be separated against the tension of spring 22.

One end of shaft 14 is fitted with a hand 30 operating lever 30, while the opposite end of said shaft is provided with a collar 31 keyed thereto and formed with a shoulder 32 which is adapted to engage one end of a lever 33. Lever 33 is pivoted at 34 to a gear housing 35 and the opposite end of this lever is positioned in contact with the end of drive shaft 5. A spiral gear 36 is splined on shaft 5 and meshes with a spiral gear 37 arranged at right angles thereto and mounted on the end 40 of lower wringer roll shaft 38. The gears 36 and 37 are enclosed by the aforementioned housing 35. A pinion 39 mounted on shaft 38 meshes with a similar pinion 40 carried by the upper wringer roll shaft and forms a 45 drive for both wringer rolls.

In the present instance, the wringer is shown detachably clamped to a suitable upright 41 on the washing machine although it will be understood that this fastening could 50 be made permanent if so desired. The drive shaft 5 is rotatably supported adjacent the drive end thereof on a bracket 42 fastened to the washing machine and a spring 43 interposed between a collar 44 on the shaft and bracket 42, normally maintains the rolls 11 and 18 out of contact.

In operation, the washing operation having 55 been completed, the cover 2 is raised causing clutch 4 to align with drive shaft 5. The operator then enters the washed articles between the normally separated rolls 11 and 18. Due to the fact that these rolls are not revolving there is no danger of the operator being injured. After the articles are entered, the hand lever 30 is depressed which

rocks the upper roll unit about shaft 14 as an axis and brings the upper roll into wringing position with respect to the lower roll. The partial rotation of shaft 14 also causes shoulder 32 on collar 31 to engage lever 33 70 and rock the same about pivot 34 thereby forcing drive shaft 5 longitudinally against the tension of spring 43 and engage pin 45 in the end of shaft 5 in clutch member 4. Rotation of clutch member 4 is thus transmitted through shaft 5, gears 36 and 37, lower wringer roll shaft 38 and through pinions 39 and 40 to the upper wringer roll, thereby rotating said rolls in opposite directions. During the time that hand lever 30 80 is depressed the upper wringer roll will be held in yielding relation to the lower wringer roll against the tension of springs 22, hence any variation in thickness of the articles passing between the rolls will be taken care of. After the wringing operation is complete, the hand lever 30 is released and spring 43 returns the parts to normal inoperative position, such movement being limited by pins 27 engaging shoulders 28 as 90 previously described.

Having thus described my invention, what I claim is—

1. A wringer comprising a pair of supports, a roll journaled between said supports, a rod journaled in said supports, a pair of brackets carried by said rod, a roll journaled between said brackets, means for rotating said rod to move the last mentioned roll toward the first mentioned roll, spring means connected with said brackets and rod for providing a resilient support for said last mentioned roll, and means for rotating said rolls.

2. A wringer comprising a pair of supports, a roll journaled between said supports, a rod journaled in said supports, a pair of brackets carried by said rod, a roll journaled between said brackets, means for rotating said rod to move the last mentioned roll toward the first mentioned roll, and means rendered operative by movement of said rod for rotating said rolls.

3. A wringer comprising a pair of supports, a roll journaled between said supports, a rod journaled in said supports, a pair of brackets carried by said rod, a roll journaled between said brackets, spring means connected with said brackets and rod for providing a resilient support for said last mentioned roll, means for rotating said rod to move said brackets and the roll carried thereby into operative relation to the first mentioned roll, and means for rotating said rolls.

4. A wringer comprising a pair of supports, a roll journaled between said supports, a rod journaled in said supports, a pair of brackets carried by said rod, a roll journaled between said brackets, spring means connect-

ed with said rod and brackets for providing a resilient support for the last mentioned roll, means for rotating said rod to move said brackets and the roll carried thereby into operative relation to the first mentioned roll, and means rendered operative by movement of said rod for rotating said rolls.

5. A wringer comprising a pair of supports, a roll journaled between said supports, a rod loosely mounted in said supports, a pair of brackets carried by said rod, a roll journaled in said brackets, a spring engaging at each end with said brackets, adjustable means connected to said rod and to the central portion of said spring, a lever connected to said rod for rotating said brackets and the roll carried thereby about the longitudinal axis of said rod, and means for rotating said rolls.

20 6. A wringer comprising a pair of supports, a roll journaled between said supports, a rod loosely mounted in said supports, a pair of brackets carried by said rod, a roll journaled in said brackets, spring means connected with said brackets and said rod for providing a resilient support for said last mentioned roll, said brackets and elements carried thereby being movable about said rod as an axis, means for limiting such movement, and means rendered operative by movement of said brackets and elements carried thereby toward the first mentioned roll for rotating each of said rolls.

35 7. A wringer of the class described including a driving mechanism, a pair of supports, a roll journaled in said pair of supports, a rod journaled in said supports, a pair of brackets carried by said rod, a second roll journaled in said pair of brackets, means for moving one of said rolls into operative engagement with the other and means rendered operative by such movement for connecting said rolls with the driving mechanism.

40 8. A wringer of the class described including a driving mechanism, a pair of supports, a roll journaled in said pair of supports, a rod loosely journaled in said pair of supports, a pair of brackets carried by said rod and having a roll journaled therein, means

for rotating said brackets and roll carried thereby above the axis of said rod and means rendered operative by said last mentioned means for connecting said rolls with the driving mechanism.

55 9. A wringer comprising a pair of supports, a roll journaled in said supports, a rod loosely mounted in said supports, a pair of brackets carried by said rod, a roll between said brackets, said brackets being movable about said rod as an axis and means carried by said rod for moving said last mentioned roll into operative relation to said first mentioned roll.

60 10. A device as set forth in claim 9 having a power unit and means rendered operative by the movement of said rod for connecting said rolls with the power unit.

65 11. A wringer comprising a pair of supports, a roll journaled in said supports, a rod journaled in a pair of elongated openings in said supports, a pair of brackets carried by said rod, a roll journaled in said brackets, means for rotating said rod to move the last mentioned roll toward the first mentioned roll.

70 12. A device as set forth in claim 11 having means rendered operative by movement of said rod for rotating said rolls.

75 13. A wringer of the class described comprising a pair of supports, a roll journaled in said pair of supports, a rod loosely journaled in said pair of supports and spaced a slight distance from said roll, a pair of brackets carried by said rod, a second roll journaled in said pair of brackets, said brackets being provided with one or more curved projections, one or more lugs on said support arranged to be engaged by said curved projections, means for rotating said brackets and roll carried thereby about the axis of said rod, the curvature of said projections being eccentric with respect to the longitudinal axis of said rod, means for moving said last mentioned roll about the axis of said rod and means for driving said rolls.

80 In testimony whereof, I hereunto affix my signature.

LOUIS SWENINGSON.
